[57] CLAIM

The ornamental design for a distilled water dispenser, as shown and described.

DESCRIPTION

FIG. 1 is a front and left side perspective view of a distilled water dispenser showing my new design;

FIG. 2 is a front elevational view thereof;

FIG. 3 is a back elevational view thereof;

FIG. 4 is a left side elevational view thereof, the right side opposite thereto being a mirror image thereof; and
FIG. 5 is a top plan view thereof.

FIG. 3

FIG. 4

FIG. 5
